UNITED STATES PATENT OFFICE

LAWRENCE C. WALSH, OF PUTNAM, CONNECTICUT.

SEWING-MACHINE.

1,278,063.

Specification of Letters Patent.

Patented Sept. 3, 1918.

Application filed November 20, 1917. Serial No. 202,994.

To all whom it may concern:

Be it known that I, LAWRENCE C. WALSH, a citizen of the United States of America, residing at Putnam, in the county of Windham and State of Connecticut, have invented certain new and useful Improvements in Sewing-Machines, of which the following is a specification, reference being had therein to the accompanying drawing.

10 This invention relates to a device for use in connection with sewing machines and has for its object the production of a simple and efficient sewing machine whereby the usual rocking motion of such sewing machines is entirely eliminated.

Another object of this invention is the production of a simple and efficient mechanism for producing a loop or stitch whereby the pieces of cloth which are sewed together 20 may be easily held together and when necessary the stitches may be easily pulled out.

With these and other objects in view this invention consists of certain novel constructions, combinations and arrangements of 25 parts as will be hereinafter fully described and claimed.

In the drawings:—

Figure 1 is a side elevation of the stitching machine.

30 Fig. 2 is an end elevation of the stitching machine.

Fig. 3 is a section taken on line 3—3 of Fig. 1.

Fig. 4 is a section taken on line 4—4 of 35 Fig. 1.

Fig. 5 is a section taken on line 5—5 of Fig. 1.

Fig. 6 is a detail perspective of the finger for actuating the hook carrying shaft.

40 Fig. 7 is a top plan view of a portion of the main operating shaft.

Fig. 8 is a detail perspective of the bottom of the shoe carried by the needle bar.

By referring to the drawings it will be 45 seen that 1 designates the frame of the stitching machine which frame is mounted upon a suitable support as may be desired, the basis 2 of the frame 1 resting upon this suitable support. A main operating shaft

50 3 is carried by the frame 1 and this main operating shaft 3 carries a driving wheel 4 which driving wheel may be driven by means of a belt or other suitable driving means. The frame 1 is provided with a plurality of projecting fingers 5 through which 55 projecting fingers 5 works an operating

needle rod 6. This needle rod 6 carries a needle 7 at its lower end as shown clearly in Figs. 1 and 2. An operating shoe 8 is carried by this needle rod 6 and is secured thereto by means of a set screw 9. The shoe 8 comprises an elongated body portion having a longitudinally extending slot 11 formed therein in which longitudinally extending slot 11 works a pin 12 carried by the eccentric head 13. This eccentric head 13 is carried by the shaft 3 as shown in Fig. 1. It will be seen by considering Fig. 1 that the needle rod 6 may be reciprocated within the fingers 5 for raising and lowering the 70 needle 7.

A suitable throat-plate 14 is secured to the frame 1 and is provided with a suitable aperture 15 formed therein through which aperture 15, the needle 7 works.

75 A hook carrying shaft 16 is mounted upon the frame 1 below the shaft 3 and this shaft 16 carries a hook 17 at its outer end which hook 17 is held in a set position upon the shaft 16 by means of the set screw 18. The 80 shaft 16 carries a loop 19 which loop passes through the elongated slotted end 20 of the rocker arm 21. This rocker arm 21 is pivotally mounted upon the pivot pin 22 and as the rocker arm 21 is swung, the shaft 16 85 will be oscillated. The arm 21 is provided with a projecting finger 23 which projecting finger 23 engages, and is swung by the cam 24 carried by the main operating shaft 3. This loop 19 is sufficiently wide to permit the shaft 16 to have longitudinal movement upon the frame 1. This longitudinal movement is provided or produced by means of the shaft fingers 25 which are pivotally mounted upon a bracket 26 formed upon the 90 frame 1. One of the fingers 25 engages a collar 27 secured to the shaft 16 and the other finger 25 engages a cam 28 carried by the shaft 3.

The shaft 16 carries a nut 29 at its outer 100 end which is threaded upon the reduced threaded end 30 of the shaft 16 as shown clearly in Fig. 1 of the drawings.

105 The operation of the device is as follows:—

As the power is applied to the driving wheel 4, the needle 7 will be brought downwardly through the aperture 15 in the throat-plate 14 due to the rotation of the shaft 3 and the reciprocation of the needle 110 rod 6. The hook 17 underneath the throat-plate is then swung forwardly by means of

the cam 24 engaging the end 23 and rocking the arm 21. The hook 17 by this movement, will pick up the thread from the side of the needle for the purpose of forming a loop. 5 While the hook 17 is in this forwardly swung position, the finger 25 will push against the collar 27 compressing the spring 31, moving the shaft 16 longitudinally, and consequently moving the hook 17 in back of 10 the needle. As the shaft 3 continues to rotate the shaft 16 will again be rocked rearward through the medium of the cam 24 and the rocker arm 21 and when the needle is in this returned position, the fingers 25 will be 15 released from the collar 27 and the spring 31 will return the shaft 16 to its original position. This last motion releases the loop thereby completing the loop or stitch and the machine is again ready to repeat the 20 operation. A suitable thread carrying standard 32 is mounted upon the frame 1 which standard carries a spool 33 and the

standard 32 is provided with a notch 34 through which the thread may be passed to guide the same to the needle bar 6. 25

What is claimed is:—

A stitching machine of the class described comprising a frame, a needle, a driving shaft for said needle, a hook-carrying shaft carried by said frame, a hook carried by said hook-carrying shaft, fingers carried by said frame and pivotally mounted thereon for engaging said hook-carrying shaft and reciprocating said hook-carrying shaft, and a cam carried by said main shaft for engaging said fingers and swinging the same, a collar carried by said hook-carrying shaft, and a spring interposed between said collar and frame for normally holding said hook-carrying shaft in a retracted position. 35 40

In testimony whereof I hereunto affix my signature.

LAWRENCE C. WALSH.
